DESIGN FOR AN ELECTRIC STOVE

Peter Muller-Munk, Pittsburgh, Pa., assignor, by
mesne assignments, to The Silex Company,
Hartford, Conn.

Application August 15, 1947, Serial No. 140,909

Term of patent 3½ years

(Cl. D81—10)

To all whom it may concern:

Be it known that I, Peter Muller-Munk, a citizen of the United States, residing at Pittsburgh, in the county of Allegheny and State of Pennsylvania, have invented a new, original, and ornamental Design for an Electric Stove, of which the following is a specification, reference being had to the accompanying drawing, forming part thereof.

Fig. 1 is a top plan view of an electric stove embodying my new design;

Fig. 2 is a side elevational view thereof; and

Fig. 3 is a fragmentary rear elevational view thereof on a reduced scale.

I claim:

The ornamental design for an electric stove, substantially as shown.

PETER MULLER-MUNK.
